United States Patent Office.

ROBERT B. TAYLOR, OF PENSASKIE, WISCONSIN.

Letters Patent No. 98,123, dated December 21, 1869.

IMPROVEMENT IN SHINGLE-PACKER.

The Schedule referred to in these Letters Patent and making part of the same.

To all whom it may concern:

Be it known that I, ROBERT B. TAYLOR, of West Pensaukie, in the county of Oconto, and State of Wisconsin, have invented a new and useful Improvement in Shingle-Packer; and I do hereby declare that the following is a full, clear, and exact description thereof, which will enable others skilled in the art to make and use the same, reference being had to the accompanying drawings, forming part of this specification.

This invention relates to improvements in apparatus for pressing and holding the bunches of shingles for binding them, and consists of the arrangement, on a suitable bench having end walls for gauging the piling of the shingles at the thick ends, of a pair of vertically-sliding bars, a transverse pressing-bar, and a set of gear-wheels, shaft, and hand-lever, the said wheels gearing with the vertically-sliding bars, which are toothed for the purpose, in such a way that the hand-lever may be used to force the transverse bars, which are connected to the upper ends of the sliding bar, down upon the bundle of shingles across the centre, pressing and holding the bundle till fastened.

Figure 1 is a side elevation of my improved machine, and

Figure 2 is a transverse section of the same.

Similar letters of reference indicate corresponding parts.

A is the table.

B and C, the end walls for gauging the outer ends of the shingles, the thin ends of which are lapped

over a bar, D, traversing the frame at the centre between the said end-guards.

The wall C is hinged to the table, so as to be turned down to deliver the finished bundles.

E are vertically-sliding bars, rising up through the side-beams of the frame, and provided with gear-teeth below, for being worked up and down by pinions F, on a shaft, G, having a handle for turning it.

These bars are slotted above the table, and have flanges I projecting inward from the upper ends, for the control of a transverse bar, K, the ends of which take under the said flanges.

The shingles being piled in the machine, as represented in the drawing, under the bar K, to the amount required for a full bundle, may be pressed down into the compact condition required by turning the hand-lever G, by which great force may be applied. When so compressed, the fastenings may be applied in any preferred way.

After fastening, the pressure is released, the wall C turned down, and the bundle discharged.

Having thus described my invention,

I claim as new, and desire to secure by Letters Patent—

The combination, with a frame, A, and elevated central transverse bar D, of the sliding bars E, clamping bar K, shaft H, pinions, and hand-lever, all substantially as specified.

Witnesses: ROBERT B. TAYLOR.
